UNITED STATES PATENT OFFICE

171,553

PORATALE HUMIDIFIER OR THE LIKE

Robert Podall, Chicago, Ill., assignor to Berns Manufacturing Corporation, Chicago, Ill., a corporation of Illinois

Application April 27, 1953, Serial No. 24,689

Term of patent 14 years

(Cl. D62—4)

To all whom it may concern:

Be it known that I, Robert Podall, a citizen of the United States, residing at Chicago, Cook County, Illinois, have invented a new, original, and ornamental Design for a Portable Humidifier or the like, of which the following is a specification, reference being had to the accompanying drawings, forming a part hereof:

Fig. 1 is a perspective view of a portable humidifier or the like, embodying my new design, the side not shown being identical to the side shown;

Fig. 2 is a rear elevation of the same.

I claim:

The ornamental design for a portable humidifier or the like, substantially as shown and described.

ROBERT PODALL.
